HEATING APPARATUS

Eugene L. Cargill and John A. Bastion, Dallas,
Tex., assignors to The Texas Company, New
York, N. Y., a corporation of Delaware

Application May 10, 1933, Serial No. 670,230

4 Claims. (Cl. 122—338)

This invention relates in general to furnaces and more particularly to an improvement in heat distribution therein.

In vertical tube furnaces of the type wherein the tubes are adapted to be heated substantially entirely by radiant heat, even heat distribution throughout the entire lengths of the heat absorbing tubes is of paramount importance. Many furnaces of this type have been installed having heat producing means, in the nature of suitable burners, located on a level with the lower portion of the vertical heat absorbing tubes. In firing a furnace of this type, the flame streams from the individual burners are projected upwardly and radiate heat, without flame impingement, to the vertical heat absorbing tubes.

With the burners positioned on a level with the lower ends of the vertical heat absorbing tubes, the lower portions of the tubes may not receive the same intense radiant heat as higher portions. This may be due to the incomplete initial combustion of the fuel at the mouths of the burners and also for a distance thereabove which limits heat radiation from the flame in this particular section of incomplete combustion.

In accordance with this invention more heat may be applied to the bottom portions of the tubes than in the past in order to more evenly distribute the heat throughout the length of tubes thereby increasing the overall operating efficiency of the furnace and avoiding any possible overheating of the upper portions of the tubes. The invention may be accomplished by positioning a suitable heat radiating and reflecting surface within the burner ring normally employed for heating the furnace. In this manner heat may be radiated as well as deflected to the lower portion of the tubes.

In order to make the invention more clearly understood, there is shown in the accompanying drawing, means for carrying the same into practical effect without limiting the improvements in their useful applications to the particular structure, which, for the purpose of explanation, has been made the subject of illustration.

Figure 1 is an elevational view, partly in section, showing a vertical furnace embodying my invention.

Figure 2 is a view, in plan, taken along lines 2—2 of Figure 1.

Referring to the drawings wherein the same parts are represented by like characters throughout the views, and more particularly to Figure 1, there is shown a furnace having a combustion chamber 1. The combustion chamber 1 may be

defined by suitable side, top and bottom walls; the side wall being indicated by the numeral 2, the top wall by the numeral 3 and the bottom wall by the numeral 4. A lining 5 of insulating material in the nature of suitable refractories may be provided for protecting the side walls 2 and the bottom wall 4. While a lining is shown as being applied to the side and bottom walls, it is to be clearly understood that it might also be applied to the top 3.

A plurality of burner ports 6, equally spaced around the center of the bottom of the furnace in a ring or circle, may be provided for receiving suitable burners 7 positioned in each. The burners 7 may be supplied with any suitable type of fuel, such as liquid, gas or solid fuel, with the necessary air to aid combustion being admitted in any suitable manner through the burner ports 6. A single supply pipe may feed the fuel to the burners. As will be noted from Figure 1, the burners are adapted to direct the flame stream from each upwardly to distribute the heat produced by each throughout the length of the combustion chamber. The hot gases resulting from the combustion of the fuel pass upwardly through a suitable insulated flue 8 to a stack 8' from which they are conducted to the atmosphere. If desired, suitable means may be provided in the stack 8' for utilizing any remaining heat in the flue gases. For instance, an air preheater and/or an economizer may be positioned in the stack 8'.

A plurality of vertical heat absorbing tubes 9 may be positioned within the combustion chamber 1 and are adapted to be heated substantially entirely by radiant heat produced by the upwardly projecting flame streams from the plurality of burners. The heat absorbing tubes 9 may pass through both the top and bottom walls of the combustion chamber and may be connected by suitable return bends 10. In order to avoid cooling of the fluid passing through the return bends 10, suitable means may be provided. As shown, the return bends 10 may be located in heat insulating chambers 11 positioned exterior of the combustion chamber 1. The chambers 11 may be provided with removable covers 12 to permit ready access thereto. The same type of insulated chambers may be provided for both the upper and lower return bends.

The furnace proper may be supported by suitable standards 13 resting upon a base 14. Additional standards 15 may be provided for the furnace, these standards lending additional support

to the bottom of the furnace in which the burners are installed.

In the past it has been customary to fire a furnace of the type described by projecting the flame stream from each burner upwardly in an unobstructed path. With this method of operation, the flame stream from each burner projecting upwardly passes through a relatively short distance before complete combustion thereof is obtained. 5
Without complete combustion of the flame stream at the beginning thereof, the maximum heat intensity is not obtained resulting in less heat being radiated to the lower portions of the heat absorbing tubes 9 than to other portions thereof, therefore 10
by resulting in possible overheating of the upper portions of the tubes. In accordance with this invention, the lack of intense heat to the lower portions of the tubes is obviated and the entire length of the tubes evenly heated throughout their 15 lengths.

The invention may be accomplished by providing a suitable heat radiating and deflecting surface within the ring or circle defined by the plurality of burners. As shown in Figure 1, a heat 20
radiating and reflecting surface 16 corresponding in shape to the shape of the combustion chamber may be provided. The heat radiating and reflecting surface 16 may consist of a plurality of 25
refractory bricks 17 suitably cemented together to provide an inner cylinder within the combustion chamber. In constructing the refractory wall, the 30
bricks 17 may be arranged so that every other course thereof is a header course, in other words, the courses may alternate between header and 35
stringer courses.

As shown in the drawings, the refractory wall inside of the ring or circle defined by the plurality of burners does not extend very high into the combustion chamber. It has been found that in operating 40
a furnace of the type described in which the combustion chamber has a height of about 30 feet, more or less, the refractory wall will produce satisfactory and unexpected results if only constructed to a height of about 6 to 8 feet. The 45
diameter of the refractory surface within the combustion chamber is likewise smaller in comparison with the diameter of the combustion chamber proper and if the diameter defined by the inner circle of tubes 9 is about 17 feet, it is only necessary to provide an inner refractory surface of about 4 or 5 feet in diameter. 50

While certain dimensions have been set forth that may advantageously be employed in constructing a furnace in accordance with the invention, it is to be clearly understood that these are merely for the purpose of explanation and may be varied without departing from the spirit or the scope thereof. For instance, compressed air may be utilized in aiding combustion which would decrease the distance through which the flame streams project before complete combustion, or, if desired, a special type of burner may be employed to obtain rapid complete combustion. The invention may be applied to a furnace of the type described operating in any manner, the particular size and shape of the refractory wall depending upon the particular operating conditions and size and shape of the furnace proper. 65

In lieu of cementing the bricks 17 tightly together in order to form a solid refractory wall, the individual bricks may be arranged in a check-70
erbrick work manner. By this arrangement, it will be possible to cut down the cost of the refractory wall. If desired, an additional burner 75
may also be provided and positioned within the

refractory wall to increase the amount of radiation therefrom.

Any suitable type of refractory material, such as fire brick or the like, may be used. The invention also contemplates the use of any other suitable type of radiating and reflecting surface, such for instance, as metal or metal alloys. Any suitable metal or alloy may be employed, but it is preferred to use one which satisfactorily resists corrosion and oxidation, such as chromium 10
and/or its alloys. 15

In operating the improved furnace, the flame streams from the burners project upwardly and the distance through which they may be projected before complete combustion will vary depending upon the type of burners employed and the amount of air used to aid combustion. The burners, as shown in the drawings, being closer to the refractory material comprising the wall than the heat absorbing tubes, heat it to a greater extent. The upper portion of the wall is heated to a greater extent than the lower portion which provides for additional heat being conducted from the upper to the lower portion of the refractory wall. The entire wall being intensely heated by 25
the flame streams radiates heat to the lower portion of the heat absorbing tubes in proximity thereto thereby increasing the heat input to the tubes. Moreover any impingement of the flame and hot products of combustion against the refractory wall aids complete combustion of the fuel and results in the hot products being deflected outwardly towards the lower portion of the tubes thereby also providing additional heat. If desired, the refractory wall may be flared outwardly 30
from the bottom thereof to a slight extent in order to provide for additional heat deflection. 35

The hot products of combustion after passing through the section of the combustion chamber provided with the heat radiating and reflecting 40
surface are merged and extend through the remainder of the combustion chamber in a column of substantially uniform cross-section. The column of hot products of combustion evenly radiate heat to the tubes surrounding it thereby evenly 45
heating the fluid passing through the tubes predominantly by radiant heat.

While there is shown and described a furnace of circular cross-section, it is to be clearly understood that the invention is not limited to a 50
furnace of this particular shape, as it will be obvious to those skilled in the art that the invention is applicable to a furnace of any particular shape. Moreover, the invention is applicable to a furnace in which the flame is projected 55
downwardly from the top thereof.

From the foregoing it will be apparent that this invention makes possible the operation of a vertical tube furnace in such a manner as to evenly distribute the intense radiant heat to the entire 60
length of the heat absorbing tubes. By evenly distributing the heat to the heat absorbing tubes, local overheating is obviated and more rapid and even heating of the fluid passing through the tubes is accomplished. It has been found that in 65
heating hydrocarbon oils passing through heat absorbing tubes in a furnace of the type described, it is possible to increase the throughput of the oil with as high a rate of heat input as in the past, which obviously affords a more efficient 70
furnace structure.

While there is shown and described the preferred embodiment of the invention, it is to be understood that the invention is not confined to the precise details of construction herein set forth, 75

by way of illustration, as it is apparent that many changes and variations may be made therein, by those skilled in the art, without departing from the spirit thereof, or exceeding the scope of the

5 appended claims.

What we claim is:

1. In a furnace, a vertical combustion chamber, a plurality of burners positioned at the bottom of said combustion chamber for producing hot products of combustion and directing them upwardly through the combustion chamber, a plurality of vertical heat absorbing tubes extending from top to bottom of said combustion chamber and adapted to be heated throughout their length 15 preponderantly by radiant heat from said combustion products, means in the lower portion of said combustion chamber surrounded by the lower portion of said vertical tubes directly exposed to the hot products of combustion from each 20 burner to absorb heat therefrom and radiate absorbed heat to said lower portion of the vertical tubes to increase the total heat input thereto, said means being free from direct association with fluid containing sources which would normally absorb heat therefrom and decrease the temperature thereof and extending within the combustion chamber for less than 25 about half of the height thereof to thereby permit the combustion gases from each burner after being exposed thereto to be substantially completely combined thereabove to pass through the remainder of the combustion chamber in an unobstructed path to thereby heat the remaining portion of the vertical tubes preponderantly by 30 radiant heat.
2. In a furnace, a vertical combustion chamber, a plurality of burners positioned at the bottom of said combustion chamber for producing hot products of combustion and directing them upwardly through the combustion chamber, a plurality of vertical heat absorbing tubes extending from top to bottom of said combustion chamber and adapted to be heated throughout their length preponderantly by radiant heat from said combustion products, a refractory wall in the lower 40 portion of said combustion chamber surrounded by the lower portion of said vertical tubes directly exposed to the hot products of combustion from each burner to absorb heat therefrom and radiate absorbed heat to said lower portion of the vertical tubes to increase the total heat input thereto, said refractory wall being free from direct association with fluid containing sources which would normally absorb heat therefrom and decrease the temperature thereof and extending within the combustion chamber for less than 45 about half of the height thereof to thereby permit the combustion gases from each burner after being exposed thereto to be substantially completely combined thereabove to pass through the remainder of the combustion chamber in an unobstructed path to thereby heat the remaining portion of the vertical tubes preponderantly by 50 radiant heat.

the remainder of the combustion chamber in an unobstructed path to thereby heat the remaining portion of the vertical tubes preponderantly by radiant heat.

3. In a furnace, a vertical combustion chamber, a plurality of burners arranged in a circle at at the bottom of said combustion chamber for producing hot products of combustion and directing them upwardly through the combustion chamber, a plurality of vertical heat absorbing tubes extending from top to bottom of said combustion chamber and adapted to be heated throughout their length preponderantly by radiant heat, a vertical refractory wall within the circle defined by the burners surrounded by the lower portion of said vertical tubes and directly exposed to the hot products of combustion from each burner to absorb heat therefrom and radiate absorbed heat to said lower portion of the vertical tubes to increase the total heat input thereto, said refractory wall being free from direct association with fluid containing sources which would normally absorb heat therefrom and decrease the temperature thereof and extending within the combustion chamber for less than 20 about half of the height thereof to thereby permit the combustion gases from each burner after being exposed thereto to be substantially completely combined thereabove to pass through the remainder of the combustion chamber in an unobstructed path to thereby heat the remaining portion of the vertical tubes preponderantly by 25 radiant heat.

4. In a furnace, a vertical combustion chamber, a plurality of burners positioned on the bottom of the combustion chamber, a plurality of vertical heat absorbing tubes within said combustion chamber, the lower portion of which surround said burners, and means arranged closer to said burners than to said lower portion of the tubes 35 adapted to absorb heat from combustion products from said burners and radiate absorbed heat therefrom to the lower portion of said vertical tubes, said means being free from direct association with fluid containing sources which would normally absorb heat therefrom and decrease the temperature thereof and affording a surface for at least partial impingement of the combustion products for up to about half the height of the combustion chamber to thereby effect more 40 complete combustion thereof in the lower portion of the combustion chamber and permitting the combustion gases to be substantially combined thereabove to pass through the remainder of the combustion chamber in an unobstructed path to thereby heat the remaining portion of the vertical tubes preponderantly by 45 radiant heat.

EUGENE L. CARGILL.
JOHN A. BASTION.
